(57) **CLAIM**

The ornamental design for a cap for gas appliance vent, as shown and described.

DESCRIPTION

FIG. 1 is a pictorial view of a first embodiment of a cap for gas appliance vent according to the present invention with mounting flanges not forming a part of the invention shown in phantom lines.

FIG. 2 is a front elevational view of the cap for gas appliance vent shown in FIG. 1 with the mounting flanges shown in phantom lines, the rear and side views being identical.

FIG. 3 is a bottom view of the cap for gas appliance vent shown in FIG. 1 with the mounting flanges shown in phantom lines.

FIG. 4 is a top view of the gas appliance vent shown in FIGS. 1-3.

FIG. 5 is a pictorial view of a second embodiment of a cap for gas appliance vent according to the invention with a mounting plate not forming a part of the invention shown in phantom lines.

FIG. 6 is a front view of the cap for gas appliance vent shown in FIG. 5 with the mounting plate not forming a part of the invention shown in phantom lines.

FIG. 7 is a left side view of the cap for gas appliance vent shown in FIGS. 5 and 6 with a mounting plate not forming a part of the invention shown in phantom lines.

FIG. 8 is a right side view of the cap for gas appliance vent shown in FIGS. 5-7, with a mounting plate not forming a part of the invention shown in phantom lines.

FIG. 9 is a bottom view of the cap for gas appliance vent shown in FIGS. 5-8, with a mounting plate not forming a part of the invention shown in phantom lines; and, FIG. 10 is a top view of the cap for gas appliance vent shown in FIGS. 5-9.
